UNITED STATES PATENT OFFICE.

JOHN A. MORRISON, OF MANSFIELD, OHIO.

LIFTING JACK.

Application filed October 12, 1925. Serial No. 61,963.

This invention relates to jacks such as are used for raising automobiles in order to permit a tire to be removed or repaired, and more particularly to a jack especially adapted for use upon vehicles equipped with "balloon tires", in which it is necessary to provide for a greater lifting range than is necessary for the standard type of tire.

It is customary to use a wheel of small diameter for balloon tires, as the cross sectional diameter of the balloon tire is considerably greater than that of the ordinary tire, thus requiring a greater lifting range than is necessary for standard tires.

The applicant has devised and patented jacks for providing a sufficient lifting range to properly handle vehicles equipped with balloon tires, such jacks comprising a lifting bar made up of two or more members and involving a greater expense in manufacture than that required to make the ordinary single lifting jack.

The objects of the present invention are to provide a lifting jack having any necessary lifting range required to handle a vehicle equipped with balloon tires, a single lifting member being provided for raising the vehicle to the desired height; to provide a lifting head upon one side of the lifting member for engagement with the spring or axle of the vehicle; to provide means for swinging the lifting head into various positions around the jack to permit the jack to be operated from any desired position relative to the vehicle; to provide means for holding the spring or axle of the vehicle in engagement with the lifting member and to prevent the jack from tilting or tipping under the weight of the vehicle when the lifting member is raised.

The above and other objects may be attained by providing a hollow base having vertical, spaced ribs upon its exterior, a screw being located within the base and arranged to be raised by means of a nut; a lifting arm being swiveled to the upper end of the screw and provided with a groove or channel for engagement with any of said ribs and having a lifting head located near its lower portion; and said ribs may be provided with T flanges for engagement with a C flange upon the lower end of the lifting arm.

An embodiment of the invention is illustrated in the accompanying drawings, in which—

Figure 1 is a side elevation of a lifting jack embodying the invention, parts being broken away for the purpose of illustration;

Fig. 2, a section on the line 2—2 Figure 1; 60

Fig. 3, a side elevation of a slightly modified form of the invention, and

Fig. 4, a transverse section on the line 4—4, Fig. 3.

Similar numerals indicate corresponding parts throughout the drawings.

The lifting jack includes the hollow base 1, having the pedestal portion 2, and provided, preferably at intervals of 90 degrees, with the radial, vertical ribs 3, which may be of cross sectional T shape, as shown in Figures 1 and 2.

A bracket 4 is formed in the upper end of the hollow base and a rotatable nut 5 is mounted within said bracket and receives the lifting screw 6 which normally extends into the hollow base and is provided with a transverse pin or lug 7 slidably engaging vertical grooves 8, within the base, for preventing rotation of the screw.

A ball race, as indicated at 9, may be provided between the rotatable nut and the upper end of the base to receive the thrust of the lifting screw. The nut 5 has a bevel pinion 10 formed thereon and meshing with a bevel pinion 11 fixed upon a short shaft 12, which is journaled in the angular boss 13, formed upon the bracket 4, and provided with a socket 14 to receive the shank of the usual operating handle.

The lifting arm 15 is provided at its upper end with the right angle portion 16, swiveled to the upper end of the lifting screw 6. As shown in Figure 1 this lifting arm may be provided with a socket 17 adapted to receive the reduced shank 18, of the lifting screw, a split spring ring 19 being received in the annular grooves 20, formed in the shank and socket, whereby the arm is rotatably mounted or swiveled upon the screw.

If desired this swivel connection may be formed as shown in Fig. 3, wherein the angle portion 16 of the lifting arm is provided with an opening 21, which loosely fits 105 upon the reduced shank 22 of the screw, a

coil spring 23 being located around said shank between the lifting arm and the head 24.

The ribs 3, as shown in Figs. 1 and 2, may 5 be provided with **T** flanges 25 to receive the **C** flanges 26 formed at the lower end of the lifting arm 15, whereby the arm will be held in sliding engagement with the rib as the screw is raised. If desired the flanges 3 may 10 be straight as shown in Figs. 3 and 4 and the lifting arm 15 may have a longitudinal groove or channel 27 in its inner face for engagement with any of the ribs 3.

The lifting head 28 is mounted upon a 15 bracket arm 29, formed near the lower portion of the lifting arm and at a convenient height to be received beneath the spring or axle of an automobile when in the lowered or normal position.

20 Since the lifting arm is swiveled upon the screw, it will be seen that the arm may be swung around the base and engaged with any one of the ribs 3 thereon in order that the lifting head may be located at either side 25 or directly in front of the base, thus permitting the operator to stand near the end of the automobile and engage the jack with either spring or the axle as desired.

The spring or axle engaged by the lifting head 28 may be located in engagement with the adjacent side of the lifting arm, thus preventing tilting or tipping of the jack as the lifting arm is raised. This engagement of the spring or axle with the lifting arm 35 will tend to hold the arm in engagement with the rib upon the base, this being especially useful with the type of jack shown in Figs. 3 and 4.

I claim:

40 1. A lifting jack including a base, a lifting member carried thereby, an arm suspended at its upper end from the lifting member and provided with a lifting head, and cooperating means upon the base and arm for causing said arm to travel in any one of a plurality of definite paths as the lifting member is raised.

45 2. A lifting jack including a base, a lift-

ing member carried thereby, an arm swiveled at its upper end to the lifting member and 50 provided with a lifting head, and co-operating, engaging means upon the base and arm for causing the arm to travel in any one of a plurality of definite paths as the lifting member is raised. 55

3. A lifting jack including a base, a lifting member carried thereby, an arm swiveled at its upper end to the lifting member and 60 provided with a lifting head, and co-operating, engaging means upon the base and arm for causing the arm to travel in any one of a plurality of definite paths as the lifting member is raised.

4. A lifting jack including a base, a lifting member carried thereby, a lifting arm swiveled at its upper end to the lifting member and 65 provided with a lifting head, means for swinging the arm to a plurality of definite positions around the base, and means for holding the arm in any of these positions as 70 the lifting member is raised.

5. A lifting pack including a base having a plurality of vertical ribs thereon, a lifting member carried thereby, an arm connected at its upper end to the lifting member and 75 provided with a channel for selectively engaging any of said ribs, and a lifting head upon the arm.

6. A lifting jack including a base having a plurality of vertical ribs thereon, a lifting member carried by the base, an arm swiveled at its upper end upon the lifting member and provided with a channel arranged to engage any of said ribs, and a lifting head carried by the arm. 80

85 7. A lifting jack including a base having a plurality of vertical **T** ribs thereon, a lifting member carried by the base, an arm swiveled at its upper end upon the lifting member and provided with a **C** channel arranged to engage any of said **T** ribs, and a lifting head carried by the arm. 90

In testimony that I claim the above, I have hereunto subscribed my name.

JOHN A. MORRISON.
